UNITED STATES PATENT OFFICE.

WILLIAM ENRIGHT, OF DETROIT, MICHIGAN.

FLANGING-MACHINE.

No. 802,804.

Specification of Letters Patent.

Patented Oct. 24, 1905.

Application filed September 26, 1903. Serial No. 174,758.

To all whom it may concern:

Be it known that I, WILLIAM ENRIGHT, a citizen of the United States, residing at Detroit, county of Wayne, State of Michigan, have invented a certain new and useful Improvement in Flanging-Machines; and I declare the following to be a full, clear, and exact description of the invention, such as will enable others skilled in the art to which it pertains to make and use the same, reference being had to the accompanying drawings, which form a part of this specification.

This invention relates to flanging-machines, and has for its object an improved machine adapted to bend and stretch the metal and produce flanges on a large tube of metal.

In the construction of large tanks and stand-pipes and similar vessels that are intended to contain large quantities of liquids the structure is made in sections bolted together. It is desirable to prepare the metal sections of the tank with flanges that are bent outward or inward at the ends of each cylindrical section and arranged so that contiguous sections may be secured together with rivets or bolts that pass through contiguous flanges; and the object of this invention is to produce an adjustable machine capable of turning such flanges on cylinders or barrels of different lengths and of different radii.

In its general features the machine comprises two rolls that act as a rolling vise or rolling holder for the metal that has been previously bent to tubular form. Provision is made to add to the rolls, so that a tubular body of any desired length within the capacity of the machine may be flanged, and the entire framework which supports the rolls must necessarily be adjusted to correspond with the length of the selected roller. Provision is made also to support a sheet of metal bent in tubular form and to use tubes or barrels of different diameter with quite a large range of capacity, and provision is made to adjust and regulate the several working parts of the machine to perform their duties properly with any one of the selected sizes, either as to length or diameter.

In the drawings, Figure 1 is a plan view of part of the machine. In the view shown here the machine is shown as expanded to its full capacity and contains three auxiliary pair of vise-rolls in addition to the main pair of vise-rolls. Fig. 2 is a section of a tubular body with the flanges turned thereon. Fig. 3 is a plan view of the machine, showing details of

the main driving mechanism. (The beam companion to 21 is omitted.) Fig. 4 is a plan view of a part of the inner frame. (The means for holding the two vise-rolls yieldingly together is here shown.) Fig. 5 is a longitudinal vertical section showing the steady-arms by which the tubular body is held. Fig. 6 shows the parts connected with the arbor on which the flanging-roll revolves. Figs. 7, 8, 65 and 9 are details of parts of the steady-arm shown in Fig. 12. Figs. 10 and 11 are details of the holding device shown in Fig. 4. Figs. 12 and 13 are longitudinal sectional views showing in detail a steady-arm, several 70 of which are seen in end elevation in Fig. 5. Figs. 14, 15, 16, 17, and 19 show details of several of the parts shown in Fig. 6. Fig. 18 is a horizontal section of the device by which the flanging-roll is swung. 75

In the machine which embodies this invention there is an external framework. There are two rolls which are utilized to hold the shell or barrel of tubular metal that is under treatment. The two rolls will be hereinafter called the "vise" or the "rolling vise." The effective length of this vise may be varied by adding auxiliary rolls on the roll-shafts. One of the roll-shafts is journaled at one end in the main frame, and the other end is journaled in a bearing that is slidingly supported in a bracket. The bracket is built out from the main frame. The other roll-shaft is supported at both ends in an auxiliary frame that has a sliding movement longitudinal of the main 90 frame.

The main frame is made with two heavy built-up side frames, one of which, located at the rear of the machine, (the side which is shown at the top in Fig. 3 and shown in elevation in Fig. 5,) is built of longitudinal stringers 21, corner-posts 18 and 19, with suitable intermediate posts 17, and brace 16, bottom stringer 2, and horizontal intermediate stringers 2^a. The other side frame, at the front of the machine, is shorter, and the heavy top stringer 21 is omitted from this front beam. The front beam carries one end of the shaft 14 and supports the ways for some of the adjustable parts which will be described, 105 but does not support the heavier parts of the mechanism. The two side beams are secured together by suitable cross-bars A. The side beams support horizontal brackets 3^a, on which rest side beams 71 of an inner movable 110 frame. The side beams 71 are connected by cross-beams 22 and 23 and cross-beams B and

C, all of which are provided with numerous bolt-holes and which hold securely the remaining parts which comprise the inner frame, one part of which on the side R remains fixed in position with respect to side bar 71. The other part on the side L is shifted to bring this side of the inner frame to its proper place with reference to the number of auxiliary rolls that are in use.

- 10 Outside the main framework is the driving mechanism which communicates motion from any suitable source of power from driving-wheel 135, through clutch 35 on driving-shaft 34 and chain of gearing from pinion 36, to gear 37 on the shaft 13 of roll 3. A gear 131 on the shaft 13 meshes with gear 141 on the shaft 14 of roll 4, and the power thus communicated to the machine drives the rolls 3 and 4 in opposite directions. The other actuating mechanism of the machine may be manipulated or may be power-driven. It is shown in the drawings as hand-driven. One end of the shaft 13 is held in bearings in the right side beam, and to this right side beam 25 is secured a bracket 11, which supports a sliding bearing 12, held in its selected position to the bracket by bolts. One end of the shaft 14 is held in bearings in the right side of the inner frame, and the other end is 30 journaled in the sliding part of the inner frame at the left end of the roll.

The cross-beams 22 and 23 and C and Bare provided with bolt-holes 24, through which pass the bolts which secure the inner frame 35 together, and the length of each part of the rolling vise may be added to or diminished by using or laying aside one or more of the auxiliary rolls, of which rolls 31, 32, and 33 are used on shaft 13 with roll 3, and rolls 41, 40 42, and 43 are used on shaft 14 of roll 4.

The shaft 13, with the rolls mounted on it, is held in stable position. The shaft 14, with the rolls mounted upon it, is slightly movable with respect to the shaft 13 and is actuated 45 by means of screws 51 and 52. (See Figs. 4, 10, and 11.) The stems of the screws 51 and 52 pass through bearings 8 in the cross-bar A, which is a cross-bar of the main frame, and the stems are journaled in this cross-bar, 50 and each is slightly movable along its own axis, but is normally held projected inward, bearing against the sliding inner frame by the tension of springs 54, each of which encircles the stem of its proper screw and each 55 of which bears against the cross-bar A and the collar 53 on its proper screw. Each of the screws is provided with a sprocket-wheel 152, and the two sprocket-wheels are coupled by a chain 55, so that both the screws are actuated simultaneously by means of the hand-wheel 56.

The tubular body of metal on which the flange is turning is placed between the rolls 3 and 4 of the rolling vise and rests on steady- 65 arms that are held to the right frame-beam.

The inner surface of the tube engages against supporting-rolls 50, 60, 70, 80, and 90, which, with the brackets that support them, are adjustable to accommodate different sizes of tubes. The flanges are turned by rolls 61 and 62, which are similar in construction and similarly actuated. Both the flanging-rolls are swung to allow the tubular body which is to be treated to be inserted between the rolls 3 and 4, and both have a horizontal 75 movement radial with respect to the roll 4, which movement takes place during the progress of turning the flange. The rolls are actuated along this radial path as the flanges are formed. The two movements will be best 80 understood by examining Figs. 6, 14, 15, 16, confining the description to the mechanism connected with the flange-turning roll 62, which is similar in all respects to the mechanism connected with the flange-turning roll 85 61. The roll 62 is carried on a hollow hub 86, that projects from a yoke 72. This hollow hub 86 and the yoke slide on an arbor 64, that is pivotally connected by pivot 65 to the auxiliary frame, whose side beams 71 slide on 90 track 67, supported on bracket 3^a. The unpivoted end of the arbor 64 engages through yoke 72 on the frame, and the slide-rods 68 and 69 are themselves each made in two parts united by pivots 75, which permit the end of the frame 95 and the arbor 64 to swing when the pivots 65 and 75 are in axial alinement. The end of the arbor 64 is supported in a bearing 76. (See Fig. 16.) The bearing is swiveled in a fork 77, 100 the stem of which is provided with a screw 77^a and extends through a journaled nut 78 on the auxiliary frame. On the outer end of the nut there is a sprocket-wheel 79, connected by a sprocket-chain to wheels 81, and the wheels 81 are on cross-shafts 5, connecting 105 the two similar frames which carry the two rolls 61 and 62. The slide-bars 68 and 69 are connected by cross-head H, through which runs a screw 82, swiveled to the frame of 110 vise-roll 4 by connections shown at 83. On the screw 82 is a sprocket-wheel 84, by which the actuating-screw is connected with and made to act contemporaneously with the corresponding screw in connection with roll 61. An actuating hand-wheel 95, through sprocket-wheels 81, engages the chains to actuate the 115 sprocket-wheels 79 and nuts 78 simultaneously. The hub 86, with the flanging-roll journaled thereon, slides on the arbor 64, and the frame-bars engage through guides 87 and 120 88, so that the frame, hub, yoke, and roll move together, while the screw 82 remains practically fixed in position, although revolvable. At the junction between the fork 77 and bearing 76 there is provision made for play of 125 the parts by engaging the trunnion-screws of bearing 76 through oval slots 177 in the branches of the fork 77. The loose engagement allows the screw 77^a to maintain its position with respect to the frame and allows 130

the arbor 64 to swing as the screw 77^a is advanced along its own axis.

The tubular body under treatment is held on the rolls 50, 60, 70, 80, and 90, and these 5 are adjustable to correspond with the size of the tube under treatment. The means of this adjustment will be understood from an examination of Figs. 5, 12, 13, 7, 8, and 9. There are several diverging rail-guides, one for each steady-roll. Each rail-guide has a flanged track 101, on which engages a grip 102. To the grip is secured a plate 103, in which there is a circular groove 104. The grip-plate is held in its adjusted position on the track by set-screws 105 and 106. The circular groove 104 is undercut, and a circular plate 107 rests on the front of the plate 103 and is held by bolts 108, whose heads engage under the flanges which overhang the groove 104, and by means of the bolts the plate is held in any position of rotary adjustment. The plate 107 supports a bracket 111 and above the bracket has a bearing eccentric to its center, in which is journaled one end of 5 the shaft 110 of roll 109. The outer end of the shaft 110 is journaled in the end of the bracket-arm 111. With this construction the bracket can be adjusted around the shaft so as to bring a surface of the steady-roll 109 to contact the inner surface of the tubular body under treatment and so as to swing the bracket to a position that the arm part of it will not contact the surface of the tubular body.

The operation of the machine is as follows: The machine is set to the desired width. The rolls 50, 60, 70, 80, and 90 are adjusted to the proper circle for the tubular body which is to be flanged. The inner frame is drawn back to spread the vise-rolls, and the flanging-rolls 61 and 62 are swung outward until the tubular body D to be treated can be inserted over the roll 3 and its shaft and supporting-bracket. The inner frame is next forced inward until the tubular body is gripped closely between the rolls 3 and 4. The flanging-rolls 61 and 62 are swung inward, and the machine is set in motion, causing the tubular body D to rotate on its own axis. While thus rotating the slide-bars 68 and 69 are drawn to force the flanging-rolls 61 and 62 radially outward from the axis of rotation of the tubular body D or from the axis of rotation of the roll 3, and the combined rotation of the tubular body and the flanging-rolls, which is brought about by

frictional contact with the bending-flange of the tubular body, forces the flange outward until it lies at the desired angle with the body of the tubular body. The inner frame is then drawn backward to spread the rolls 3 and 4, 60 to the flanging-rolls turned outward, the flanged tubular body removed, and another one inserted.

What I claim is—

1. In a flanging-machine for metallic tubes, 65 the combination of a rolling vise, means for rotating the vise members and a radially-movable flanging-roll movable along a radius of the vise-roll, substantially as described.

2. In a machine for flanging tubular bodies, 70 the combination of a rolling vise, means for rotating the rolling vise, a flanging-roll movable along a radius of a vise-roll, and a hinged frame for said flanging-roll, substantially as described.

3. In a machine for flanging tubular bodies, 75 the combination of a rolling vise, a flanging-roll on an arbor that is radially movable with respect to a member of said rolling vise, means for producing radial movement of the flang- 80 ing-roll, and means for swinging the flanging-roll, substantially as described.

4. In a machine for flanging tubular bodies, 85 in combination with a rolling vise to hold said tubular body, a flanging-roll mounted on an arbor radially movable with respect to a member of said rolling vise, a pivotal connection for said arbor, and means for holding and controlling the unpivoted end of said arbor, 90 substantially as described.

5. In a machine for flanging tubular bodies, 95 the combination of a main framework, a member of a rolling vise mounted on said main framework, a movable inner frame, a second member of a rolling vise mounted on said inner frame, and means for actuating the inner frame, substantially as described.

6. In a machine for flanging tubular bodies, 100 in combination with a main framework, a vise of rolling members, auxiliary rolls for increasing the length of the vise, and means for adjusting the holding-frames to correspond with the number of auxiliary rolls employed, substantially as described.

In testimony whereof I sign this specification in the presence of two witnesses.

WILLIAM ENRIGHT.
